Williams

Application December 31, 1938, Serial No. 248,734

2 Claims. (Cl. 68—269)

This invention relates to a clothes wringer of the multiple bite type and is more particularly directed to a three-roll clothes wringer in which clothes are alternatively fed from either side of the wringer through one bite as an auxiliary bite and through another as a pressure wringing bite. Reference is hereby made to our application, Serial No. 453,898 filed August 6, 1942.

In wringers of this type heretofore constructed it has been found desirable to provide mechanism by which a single movement of a control handle will control both the roll drive and the application of pressure thereto.

It has been the chief object of our invention to provide a wringer of this nature in which such control is simplified and in which the control may be operated with less pressure than has heretofore been necessary.

A further object of our invention has been to provide pressure applying means shiftable from coaction with one roll bite to coaction with the other and so arranged that the line of application of spring pressure lies in a plane passing through the axes of the two rolls, between which wringer pressure is maintained.

Other objects of this invention will become apparent from the following description when read in the light of the annexed drawings and the novel features are summarized in the claims.

In said annexed drawings:

Fig. 1 is a transverse section in a vertical plane through the wringer;

Figs. 2, 3 and 4 are sections through Fig. 1 as indicated by the lines 2—2, 3—3 and 4—4 respectively;

Fig. 5 is a section indicated by the line 5—5 on Fig. 1 with parts omitted;

Fig. 6 is a section in the same plane as Fig. 5 with parts omitted but showing the mechanism in idle position;

Figs. 7 and 8 are sections indicated by the lines 7—7 and 8—8 respectively, on Fig. 6;

Fig. 9 is an end elevation of the improved wringer;

Figs. 10 and 11 are schematic showings of the release mechanism when engaged and when in position to release respectively; and

Fig. 12 is a perspective of the roll controlling pivoted end frames.

In general the wringer comprises a pair of lower rolls mounted in a horizontal plane and in position to each coat simultaneously with a top roll mounted thereabove. A power drive is supplied to act through reversing mechanism to drive the rolls in either direction desired. A shift-

able pressure spring movable from coaction between the top roll and either of the lower rolls as desired is connected to a control bar which simultaneously shifts the same and controls the direction of rotation of the wringer.

Referring now to Figs. 1 and 9, there is provided a frame formed of two U-shaped channel sections 15 and 16 welded to cross-frame members 18 and 19 at each end of the wringer. The left 10 end of the wringer, Fig. 1, is welded to a sheet metal head frame 20, in which is rotatably supported a stub shaft 22 to engage the wringer driving column on the washing machine and thus provide a power connection to drive the rolls. 15 Carried by the stub shaft 22 is a bevel gear 24 driving a second gear 25 mounted on a wringer stub shaft 27 which is journalled in a collar 29 welded to the channel frames 15 and 16 and reinforced by an underlying stirrup 31, similarly 20 connected to the channel frames.

The rolls are controlled and partially supported by a pair of pivoted end frames 35 disposed at opposite ends of the wringer. These end frames, as best shown in Figs. 1, 2, 6 and 12, each comprise 25 a plate 37 provided at the top with an inwardly extending shoulder 38 to support the pressure spring assembly as hereafter described. The plates are recessed, as best shown in Fig. 3 and indicated at 40, to form an irregular opening con- 30 verging at the center in a narrow upstanding rib 42 and a broad downwardly depending rib 44. The openings on each side of the ribs are symmetrical with the long axis of the plate and permit play of the lower rolls as hereafter described. 35 This opening, not lending itself to convenient description, is further defined as the opening included within the double line indication of the reinforcing flange 46, shown in Fig. 3.

Each of the plates 35 is further provided with 40 a seat for a wooden roll journal 48 mounted for sliding movement in the slot 50 in line with the rib 42. At its upper end the slot is enlarged to permit removal of the journal blocks which are retained in the slot against displacement by rabbits in the journals which are engaged by the sides of the slot 50.

The end frame members 37, as best shown in Fig. 12, each carry a shell 53 comprising a pair of flanges 54 bolted to the plates and through 50 generally channel shaped ribs 55 merging at the unsupported end with a vertical base plate 57.

The upper roll is urged downwardly by a spring acting with movable journals 48. This spring, as shown in Fig. 1, comprises an upwardly bowed leaf 60 engaged at its midportion by a screw 62,

to which is secured a handle 64. The screw is journaled in a boss on the plate 65 which extends across and is rigidly secured to each of the ribs 38 of the end frames 35. It will be apparent that as the handle 64 is turned the upper roll, indicated at A, will be urged downwardly by the spring 60 or released as desired to establish wringing pressure.

The lower rolls, indicated at B and C and positioned with respect to roll A as shown in Fig. 4, are alternatively locked to resist the downward movement of the roll A under the action of the spring 60 and establish wringing pressure between the top roll and either of the lower rolls.

The lower rolls are carried in substantially fixed bodily relation to each other by a pair of double journals 70 and 71 at opposite sides of the wringer. The journal 70 comprises a pair of flat plates retained in position with respect to each other by roll journals 73 brazed to each plate. A roller 74 surrounds each journal for purposes hereinafter described and the shafts 75 of the rolls B and C lie within the journals. The double journal 71 is identical with the journal 70 except that the journals 73 are longer, as indicated, and support a third plate outwardly beyond the two named.

The purpose of the elongated journals at the right-hand side of the wringer, Fig. 1, is to insure that each of the rolls B and C will remain in parallel with the other and maintain the axis of each roll in a horizontal plane even when clothes are fed between one or the other of the rolls and the roll A, causing separation at the roll bite. This is because the shafts, having a minimum clearance with the journal blocks, are limited in the amount they can move out of line with the bearing axis as the length of the bearing surface increases. Expressed in another way, if a bunch of clothes is fed between the top roll and either of the lower rolls at one end of the wringer the opposite end will drop equally with the feeding end. The purpose of this as hereinafter described is to operate the automatic stop mechanism when excess material is fed to the rolls at either end of the wringer without the necessity for duplication of release mechanism at each end of the wringer as heretofore employed. The lower rolls are normally maintained against the roll A by a light wire spring 80 bearing at the ends against channels 15 and 16 and bowed upwardly in the middle to lie in a transverse slot in lugs 82 brazed to the journals 70 and 71, respectively. One end of each spring 80 is sharply bent to lie in a hole in the channel 15 and the opposite end of each spring lies in a transverse slot in the upper edge of the bottom member of the channel 16. The springs are thus retained in position and yet allowed to contract and expand. The upward pressure exerted by these springs to maintain the rolls B and C in contact with the roll A establishes the feeding bite pressure. This pressure is heavy enough to grip and feed clothes to the pressure bite and yet is light enough to avoid injuring the fingers of the operator if they become caught therebetween. Further, the pressure is sufficiently light to permit the operator to jerk her hand out of the intake roll bite.

Sidewise movement of the lower rolls is limited by the extensions at the ends of said rolls engaging the vertical edges of the cut-out portions 82.

In connection with the two spring mechanisms discussed, namely, the pressure spring 60 and the auxiliary springs 80, it will be apparent that the

former is alternatively applied at either roll bite while the latter is continually applied at both roll bites. Thus, as the spring 60 is shifted, as hereinafter described, a wringing pressure bite is established at either side of the wringer desired and, due to the continued coaction of the auxiliary springs, the other bite is automatically retained in an intake auxiliary bite.

The pressure spring 60 is shiftable to coact with either roll bite desired in such a way as to apply its force in a line passing through the axes of the two rolls then acting as pressure rolls. This is an important feature of the invention because it applies the high roll pressure along a line permitting separation of the rolls as clothes are fed thereto in a manner to prevent binding of the movable roll journals with the supports against which they slide. The importance of this feature becomes apparent when it is recalled that wringing pressure is normally sufficient to crush the operator's hand when caught between the wringer rolls.

The pressure spring shifting is accomplished by bodily shifting the end frames 35 from a position shown in Fig. 3 through a neutral position to the position indicated by dotted lines in that figure. In the position shown in Fig. 3, the roll B is locked against movement in any direction and may only rotate in its supporting journals. Movement of the roll to the right in that figure is prevented by the contact of roller 74 carried about the journals of adjacent and commonly supported roll C against the curved side of the opening 40 heretofore described. The flange 46 surrounding this opening and shown in Fig. 7 provides adequate bearing for engagement by a roller 74 and thus, while preventing sidewise motion of the roll B, permits the roll C to drop freely as clothes are fed thereto. The roll C and the flange maintain contact because the latter is formed along an arc whose center is coincident with the axis of the roll B when in the position shown in Fig. 3.

Downward motion of the roll B in the locked position under discussion and incidental motion to the left are prevented by the narrow up-standing ribs 42 of the end frames 35 underlying the sleeve 74 of the corresponding journals. Thus, when the end frames are shifted to the position described, rolls A and B act as wringing rolls and roll C acts with roll A to provide a light pressure intake bite to the pressure roll bite. The adjustment of the handle 64, controlling the spring 60, should be set so that a slight upward movement of the lower roll, when engaged by the rib 42, applies the action of the spring to the top roll to initially load the bite with wringing pressure. As clothes are fed through the pressure bite their thickness results in upward movement of roll A against the action of the spring 60 along a line passing through the two coacting roll axes.

To shift the end frames 35 a control bar 85 is employed extending across the wringer and secured to side arms 87 which are pivoted to the face plates 57 at 88. The ends of the arms 87 carry pins 89 which lie within the vertical slots 90 of the end frame members 18 and 19. In the same manner the face plates 53 each carry two pins 91 and 92, both of which also lie within respective slots 90.

Referring to Fig. 9, it will be seen that the slot 90 is extended outwardly, as shown, to permit sidewise movement of the pins 89 and 92, respectively. The slots comprise two horizon-

fully extending regions 94 and 95 respectively, the former of which accommodates pin 89 and the latter pin 92. As the handle 85 is shifted to the dotted line position shown in Fig. 9 the pins 89 at the ends thereof ride outwardly in the left side of the openings 94 until the said pins abut the upper side thereof and limit further movement of the handle. At the same time, due to the pivot connection between shells 53 and the handle 85 at 88 and, due to the position of the pins 94 in respective slots 90, there will be a camming of the drive mechanism in a counter-clockwise direction (Fig. 2) as hereafter described. This movement carries lower pins 92 to the left (Fig. 9) until the said pins underlie the upper portion of the left-hand side of the openings 95. When the pins 89 and 92 are thus positioned the mechanism is so retained that although the pressure spring 60 is actively applied between rolls A and B (Fig. 4) there is no tendency for the handle 85 to return to an upward position. At the same time a slight pressure on the handle toward the center of the wringer will permit the wringing pressure to be released because this movement is sufficient to rock the pins 92 to clear the upper part of the right-hand-side of opening 93. When the handle 85 is swung across the wringer to the left-hand side thereof with reference to Fig. 9 the pins 89 will lie on the right-hand side of the openings 94.

As the handle is swung to either side of the wringer and the pins engage the corresponding side of the above described openings the ribs 42 of the plates 37 ride under the sleeves 74 of the roll on the opposite side of the wringer from that toward which the handle is swung. Thus, referring to Figs. 3 and 5, when the handle is swung to the right the ribs 42 engage the sleeves 74 of roll B and cam the same upwardly against roll A to force that roll slightly upwardly against spring 60 and apply wringing pressure at the roll bite between rolls A and B. When the handle is swung in the opposite direction the wringing bite is maintained between rolls A and C. In either case the bite which does not act as the wringing bite will be under light auxiliary pressure due to the action of the auxiliary springs 80.

Power is applied from the shaft 27 to drive either roll B and C as desired and, through friction therewith, to also drive the roll A. This driving mechanism is best shown in Figs. 1, 2, 5 and 6. Carried by the shaft 27 is a gear box 100 and a drive gear 102, which latter is pinned to the shaft. The gear 102 drives a gear 104 and through it a second gear 105 mounted in the gear box. The gear 104 may be positioned as shown in Fig. 5 to drivingly engage a gear 108 pinned to the shaft of roll B, and the gear 105 is likewise adapted to engage a gear 110 pinned to the shaft of the roll C. As shown in Fig. 1, the gear 104 is of sufficient width to permit engaging the gear 105 and the gear 108 in a position offset from the location of gear 102.

From the foregoing description it will be seen that as the handle 85 is shifted clockwise, (Figs. 5 and 6) drive is established to the roll B from the gear 102 through gear 104 and thence to the roll gear 108. To this end the gear box 100 becomes shifted under the influence of pin 92 on a stamping 115 (Fig. 2) hereafter described. The spring pressure between rolls A and B causes the former to be driven through the latter and in like manner the pressure of the springs 80 results in the driving of roll C due to contact with roll A. When the parts are in this position wringing pressure

will be applied between rolls A and B and the rolls will rotate in such direction that clothes may pass between the two roll bites from right to left.

To reverse the wringer it is only necessary to throw the handle 85 from the position shown in Fig. 5 through the neutral position of Fig. 6 into the dotted line position of Fig. 3. Thus the rolls A and B will be frictionally driven due to the driving of roll A by roll C. This drive occurs because the gear 105 will in this position be in mesh with the gear 110 and the gear 105 is driven through the gear 104 and the gear 102. When the gear 110 is driven there is in effect an additional gear interposed in the train and this effects a reversal of rotation over the condition when the gear 104 engages the gear 108 and the gear 105 is idle. In the position where roll C is driven the ribs 42 will underlie rollers 74 carried by the journal supporting roll C and thus wringing pressure is established between rolls A and C. Due to the direction of rotation, clothes may be fed through the roll bites from left to right.

Roll rotation ceases when the handle 85 is shifted to a neutral or vertical position. At this time the gear box 100 and the gears 104 and 105 are so positioned that there is no driving relation with either of the gears 108 or 110.

Rotation of the pressure rolls is automatically terminated upon feeding an excess thickness of material to the wringer. The means by which this is accomplished is best shown in Figs. 2, 8, 10 and 11. A U-shaped stamping 115 is formed to lie against and partially surround the gear box 100. As shown in Figs. 1 and 2, this stamping includes an elongated opening encircling the sleeve 29 carrying the stub shaft 27. This elongated opening terminates at the top in a narrow slot which embraces the pin 92 on the drive side of the wringer. The stamping is normally held upwardly against the journal 29 by a small coil spring 117, bearing at one end within the stamping and at the other end against a stud 118 threadingly secured in the bottom of the gear box.

From the description so far it will be apparent that the gear box, otherwise normally free to pivot as it would, is maintained in position by the engagement of the stamping 115 closely about it and when the pin 92 lies within the aforesaid stamping slot. The pin 92 is in turn held in position, depending on the location of the handle 85 which acts to swing the assembly in which the pin 92 is secured. It follows that if the stamping 115 is slid downwardly along the gear box 100 against the spring 117 the slot therein will no longer engage the pin 92 and the gear box will be free to pivot. When this occurs, the driving engagement between either gear 104 or 105 and respective roll gears will cease as the load on the rolls will cause the engaged gears to easily ride out of engagement with each other.

The stamping 115 is dropped and the roll rotation terminated upon movement of the lower roll acting to establish the feed bite a predetermined distance from the top roll. To this end an arm 120 is secured to the head end lug 82 of the lower roll journal and extends outwardly lengthwise of the wringer in position to overlie a pin 122 carried by the channel 115. Referring to Fig. 1 it will be seen that the opposing holes in the sides of the stamping which accommodate the pin 122 are duplicated in vertical rows to permit location of the pin at various heights with respect to the stamping. This permits adjustment of the position at which the drive is terminated when the

auxiliary lower roll moves away from the top roll. Referring to Fig. 10, the member 120 is normally positioned slightly above the upper end of the pin 122 and as thick material passes into the pressure bite, as shown in Fig. 11, the lower auxiliary roll drops away from the top roll pivoting the double roll journal blocks about the opposite lower roll. This in turn drops the member 120 until it contacts with one end of the rod 122, pushing the same downwardly and carrying with it the stamping 115. This draws the portion forming the slot surrounding the pin 92 downwardly and, as above described, releases the gear box 100 to permit the gears 104 and 108 to rotate out of engagement with each other.

As shown in the drawings, the mechanism is duplicated at each side of the wringer to permit automatic termination of the roll rotation, although the same has only been described when the wringer is positioned to feed clothes from right to left in the drawing.

A drain board 125 (Figs. 1 and 9) is pivotally secured to the main frame by pins 127 to enable it to be rocked from side to side to discharge water at either side of the wringer desired. The stud 118 engages at one side or the other of the plate 130 carried by the drain board and as the handle 85 is shifted from one side of the wringer to the other the drain board is likewise shifted.

From the foregoing description it will be apparent that this invention is directed to a novel clothes wringer which permits automatic control of the wringer drive and simple manual control

of both the wringer drive and the application of wringing pressure at the roll bite.

Other modes of applying the principle of my invention may be employed instead of the one explained, change being made as regards the structure herein disclosed, provided the means stated by any of the following claims or the equivalent of such stated means be employed.

We therefore particularly point out and distinctly claim as our invention:

1. In a wringer, a frame, a pair of rolls carried by said frame, power means to drive said rolls and mechanism to drivingly connect said rolls to said power means to rotate said rolls in either direction desired, comprising two gears carried by respective rolls, a member mounted for shifting movement transversely to the axis of said rolls, a pair of meshing gears carried by said member, a power connection to drive said gears and means to shift said member to alternatively engage one member gear with one roll gear or the other member gear with the other roll gear.
2. In a wringer, a frame, three rolls carried by said frame with their axes triangularly spaced apart and with one roll coacting with each of the other two to provide a pair of roll bites, power means to drive said rolls and a driving connection coupled with said power means and including two power take-offs rotating in opposite directions, and means to alternatively couple one of said take-offs with one of the said other two rolls to rotate the same in either direction desired.

CHARLES B. WILLIAMS.

THANKMAR WALTER KAESTNER.
